UNITED STATES PATENT OFFICE.

HENRY LAWRENCE GULLINE, WILLIAM SCHWEGEL, AND JOHN CONNOLLY, OF GRANBY, CANADA; SAID SCHWEGEL AND CONNOLLY ASSIGNORS TO SAID GULLINE.

HORSE-COLLAR.

SPECIFICATION forming part of Letters Patent No. 596,423, dated December 28, 1897.

Application filed March 25, 1897. Serial No. 629,245. (No model.)

To all whom it may concern:

Be it known that we, HENRY LAWRENCE GULLINE, WILLIAM SCHWEGEL, and JOHN CONNOLLY, of the village of Granby, in the county of Shefford and Province of Quebec, Canada, have invented certain new and useful Improvements in Horse-Collars; and we do hereby declare that the following is a full, clear, and exact description of the same.

10 This invention relates more particularly to pneumatic horse-collars, although of general application, and has for its object to improve the construction thereof, whereby any chances of the trace-hooks accidentally ripping same 15 open are reduced to a minimum, besides cheapening and simplifying to a considerable extent the manufacture of the collars.

Heretofore the leather bodies of horse-collars have been made of two halves, each composed of two like parts stitched or otherwise secured together and with a chafe-piece having one edge bound in with the outer edges of the body portions of each half, thus necessitating a seam along the body dividing the 25 liner and back portions thereof as well as locating the edge of the chafe-piece in line with such seam. After considerable experiment we have ascertained that by cutting a leather blank of a particular contour each 30 body-half can be made of a single piece and by proper manipulation given the required rounded form at the junction of the straight and crook portions without the appearance of any objectionable knobs or corners and 35 with the main seam confined entirely to the line of connection of the body with the rim of the collar, all other additional stitching being located at a point which the chafe-piece readily covers and which also allows the outer 40 edge of such chafe-piece to be stitched to the back portion of the body, so as not to overlap in any way the liner portion of such body.

For full comprehension, however, of the invention reference must be had to the annexed drawings, forming a part of this specification, in which like symbols indicate corresponding parts, and wherein—

Figure 1 is a view of the blank used to form the body-half. Fig. 2 shows such blank in folded position with the seams that are located beneath the chafe-piece stitched. Fig.

3 shows one-half of the body of a horse-collar with the chafe-piece in position. Fig. 4 is a front view of the complete collar. Fig. 5 is a back view of the complete collar; Fig. 6, 55 a side elevation thereof, and Fig. 7 a transverse section thereof on line 7 7, Fig. 5.

In carrying out our invention we use a blank of the contour shown in Fig. 1 for each half of the body and comprising "straight," "crook," 60 and "liner" sections in one piece and adapted to be folded longitudinally along the dotted line 1 into liner and back portions *a* and *b b b*, respectively. These so-called "straight" and "crook" sections comprising the back are 65 each of tapering form from their junction-point outward to their ends, and the ends of the liner portion taper also. The back portion is partially separated by a five-sided notch, presenting the opposite straight edges 70 2 2^a, adapted to be secured together, a curved edge 3, and two other curved edges 4 5, adapted to be secured to the edge 3. These several edges are secured together after the blank has been folded, as shown in Fig. 2, and it 75 will be noticed that an intermediate portion *b*' of the back is left intact between the base of the notch and the line of fold 1 of liner and back portions in order that the usual chafe-piece may have its outer edge secured to the 80 back portion in such a manner as not to overlap the liner portion in any way. The edges 2 2^a of the notch and any other parts are skived before being secured together to obtain neat joints, and they may be secured by stitching, 85 riveting, or otherwise. After the edges 2 2^a are secured together the edges 4 and 5 are whipped onto the edge 3, so that when completed and filled out the elbow or corner is of 90 perfect rounded form and entirely free from any crinkles, knobs, or points, a result not hitherto obtained in leather horse-collars, each half proper of which was in one piece. Before filling the collar the chafe-piece *d* is secured along its outer edge only by stitching *d*' or 95 riveting to the intermediate portion *b* of the back and so that such chafe-piece will extend completely over and cover up all the seams formed by securing the edges of the notch together, the side edges of the chafe-piece not 100 requiring to be secured. The two like halves of a complete body are now brought together

at the throat portion and their edges 7 overlapped and secured together, the throat-piece *e* being temporarily held in position and the edges 8 8^a of the body, as well as the edges of 5 the throat-piece and the inner edges of the chafe-pieces, brought together and stitched, thus completing the body portion of the collar. The body portion formed as described is then secured to the rim in the usual manner by stitching, lacing, or riveting along their respective meeting edges, and the collar is complete with the exception of filling and the usual pad-buckle, billet, &c.

It will be at once apparent that a much 15 stronger and cheaper collar is produced by the construction just described and that all necessity for the usual finishing welt or strip required to cover up an outer longitudinal seam is dispensed with, besides the advantage derived by the chafe-piece not reaching or overlapping the "liner" portion and so avoiding chances of ripping, &c.

What we claim is as follows:

1. A horse-collar, the body-halves of which 25 are each formed of a single piece of elbow form seamless throughout the "liner" portion and also throughout the back up to the junction of the "straight" and crook portions

thereof, and at such junction covered by a chafe-piece the outer edge of which is located 30 adjacent to but does not reach or overlap said "liner" portion, for the purpose set forth.

2. A horse-collar the leather body-halves of which are formed of a single piece of elbow form, notched on the convex edge thereof, 35 folded longitudinally and having the edges of the notch secured together and the convex and concave edges of the piece secured together to produce a complete body free from points or knobs, as set forth.

3. A blank for a horse-collar body-half, comprising an integral "straight" section, "crook" section, intermediate back section, and "liner" section, the "straight" and "crook" back sections being separated by a 45 notch, substantially as and for the purpose set forth.

Granby, Quebec, 27th day of February, 1897.

HENRY LAWRENCE GULLINE.

WILLIAM SCHWEGEL.

JOHN CONNOLLY.

In presence of—

OWEN N. EVANS,

B. STEWART PATTERSON.
